CLAIM

The ornamental design for a pump throat, as shown and described.

DESCRIPTION

FIG. 1 is a rear, right side perspective view of a pump throat of the new design;

FIG. 2 is a right side elevational view of the pump throat of FIG. 1, the left side elevational view, top plan view, and bottom plan view each being a mirror image thereof;

FIG. 3 is a front elevational view of the pump throat of FIG. 1;

FIG. 4 is a rear elevational view of the pump throat of FIG. 1; and,

FIG. 5 is a cross sectional view of the pump throat of FIG. 1, along the 5—5 line of FIG. 4.
